PORTABLE ELECTRIC POWER DRILL

William A. Douglas, South Pasadena, Calif., assignor to
The Mira Corporation, Los Angeles, Calif., a corpora-
tion of California

Filed May 8, 1964, Ser. No. 79,884

Term of patent 14 years

(Cl. D54—14)

FIG. 2.

FIG. 3.

FIG. 1 is a side elevational view of a portable electric power drill, showing my new design;

FIG. 2 is a rear elevational view of the portable electric power drill of FIG. 1;

FIG. 3 is a front elevational view of the portable electric power drill of FIG. 1;

FIG. 4 is a top view of the portable electric power drill of FIG. 1; and

FIG. 5 is a bottom view of the portable electric power drill of FIG. 1.

The side of the portable electric power drill opposite to that shown in FIG. 1 is similar to that shown in FIG. 1.

I claim:

The ornamental design for a portable electric power drill, as shown and described.
